(57) **CLAIM**

The ornamental design for an image forming apparatus, as shown and described.

DESCRIPTION

FIG. 1 is a front view of an image forming apparatus showing our new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof; and,

FIG. 7 is a perspective view thereof.

The broken lines depict environmental subject matter only and form no part of the claimed design.
